[57] CLAIM

The ornamental design for a memo holder, as shown and described.

DESCRIPTION

FIG. 1 is a perspective view of a memo holder showing our new design, the memo sheet depicted by means of broken lines being for illustrative purposes only and forming no part of the claimed design;

FIG. 2 is a top plan view thereof;

FIG. 3 is a front elevational view thereof;

FIG. 4 is a rear elevational view thereof;

FIG. 5 is an elevational view of one side thereof, the opposite side being a mirror image thereof; and,

FIG. 6 is a bottom plan view thereof.
